DESIGN FOR A TEXTILE FABRIC OR SIMILAR ARTICLE

Olga Friedman, University Heights, Ohio, assignor to William Louis Ashkenas, doing business as Cleveland Tucking and Pleating Co.,
Cleveland, Ohio

Application January 24, 1938, Serial No. 74,503

Term of patent 7 years

To all whom it may concern:

Be it known that I, Olga Friedman, a citizen of the United States, residing at 2475 Charney Rd., in the city of University Heights, county of Cuyahoga, and State of Ohio, have invented a new, original, and ornamental Design for a Textile Fabric or Similar Article, of which the following is a specification, reference being had to the accompanying drawing, forming a part thereof.

I claim:

The ornamental design for a textile fabric or similar article, substantially as shown.

OLGA FRIEDMAN.
